United States Patent Office

Des. 214,697
Patented July 15, 1969

214,697

PAIR OF SUNGLASSES OR THE LIKE

Atherton R. Mitchell, San Francisco, Calif., assignor to
Renauld International, Ltd., Fitchburg, Mass., a cor-
poration of Delaware

Filed Sept. 12, 1968, Ser. No. 13,510

Term of patent 14 years

Int. Cl. D16—08

U.S. Cl. D57—1

FIG. 1

FIG. 2

FIG. 3

FIG. 4

FIGURE 1 is a front elevational view of a pair of sunglasses showing my new design,

FIGURE 2 is a rear elevational view thereof,

FIGURE 3 is a plan view thereof and,

FIGURE 4 is a side elevational view thereof.

I claim:

The ornamental design for a pair of sunglasses or the like, substantially as shown.
